MUSICAL INSTRUMENT

Ziegner Swanson, De Kalb, Ill.

Application September 26, 1938, Serial No. 231,621

2 Claims. (Cl. 84—384)

This invention relates to a musical instrument, and particularly to a closed tube wind instrument having a flute-like tone.

The main object of the invention is to provide an instrument of the character described having means for tuning the pitch of the notes which may be produced by the player, thereby varying the pitch and increasing the usefulness of the instrument, especially for accompanying other instruments.

Another object is to provide means for facilitating the playing of the instrument by a beginner and for increasing the tone range or compass of the instrument above that initially provided.

Another object is to produce an instrument of the character described capable of producing accurately pitched notes of the scale, having soft and sweet but sonorous tonal quality. My invention is preferably embodied in instruments made of plastic material molded in a steel die, which avoids the variations and inaccuracies resulting from the use of clay-like materials which are molded while wet and then baked until dry.

In the drawing:

Fig. 1 is a top plan view of a musical instrument embodying my invention.

Fig. 2 is a longitudinal, vertical sectional view taken in the plane of the line 2—2 of Fig. 1.

Fig. 3 is an end view of the device.

Fig. 4 is a transverse section taken in the plane of the line 4—4 of Fig. 2.

In that embodiment of the invention shown in the drawing, the instrument comprises an elongated hollow body member 10, having a cylindrical portion 11 and a tapered portion 12 which terminates in a closed end 13. The inner surface of the cylindrical portion 11 is parallel with the axis of the body and is cut away to provide an internal shoulder 14. Said cylindrical portion 11 is adapted to receive a mouthpiece 15 which has a cylindrical portion 16 designed to fit within the part 11 of the body 10 and to have telescopic movement relatively thereto, as indicated by the full and dotted line positions of the mouthpiece in Fig. 2. The air inlet 17 of the mouthpiece is rectangular in cross section and of uniform dimensions. The top wall of the mouthpiece, at the inner end of the air inlet 17, is provided with an orifice 18, and the part 19 of said wall adjacent the orifice is beveled and aligned with the upper inner wall of the inlet 17, whereby the tone and accuracy of pitch of the instrument are enhanced.

The body 10 is provided with a plurality of apertures indicated at 20 to 27, inclusive, which extend through the body wall, and raised beads 28 surround each of said apertures on the exterior surface of said wall. The beads 28 aid the player in finding the openings in the body 10. The relative positions of the apertures in the body 10 and their sizes determine the pitches of the sounds produced by air passing through them. The apertures 20 to 23, inclusive, are arranged to be conveniently covered by the fingers of the right hand and the apertures 24 to 27, inclusive, are arranged to be covered by the fingers (excepting the small finger) and thumb of the left hand of the player. An instrument having the eight apertures shown provides a scale of nine notes, which is sufficient for playing by novices, and yet the instrument is not too difficult for the student to manipulate.

In order to increase the compass of the instrument at the will of the player after he has learned to use the instrument as initially produced, I have provided in the body 10 two thin wall areas 29 and 30, surrounded externally by beads similar to the beads 28. Said thin areas 29 and 30 are intended to be cut away, whereby two additional apertures will be produced, one to be covered by the small finger of the left hand and the other by the thumb of the right hand. The maximum of ten apertures provides a scale of one and one-half octaves, and the tuning provided by altering the length of the body chamber by means of the movable mouthpiece lowers the pitch and enables the player to tune his instrument to accompany other instruments,—a result not heretofore obtainable in a closed tube instrument.

The tuning device of my invention permits the player to regulate the pitch of the entire instrument, so that the pitch of the scale may be raised or lowered to conform to the scale of some other instrument, such as a piano, which is fixedly tuned. Closed tube instruments have had limited usefulness heretofore due to the fact that they could not be tuned to put them in pitch with another fixedly tuned instrument. While some open tube instruments have been provided with tuning means, such means have not been effective to vary the pitch proportionately throughout the entire range of the instrument. In open tube instruments, a sliding mouthpiece will vary the tones produced close to the mouthpiece to a much greater degree than the tones produced in that part of the instrument removed from the mouthpiece. I have discovered that by

providing a slideable mouthpiece in a closed tube instrument, I can vary the tones of the notes proportionately throughout the range of the entire instrument, the variation being such that the true tones of the scale, whether raised or lowered, are maintained in proper relationship to each other.

The dimensions of the members may be varied within limits, but it is to be understood that the 10 locations and sizes of the apertures and the air chamber proportions within the device have been carefully correlated to produce properly pitched sounds, as will be understood by those skilled in the art. For example, in the embodiment shown, 15 the body 10 is 5 $\frac{1}{8}$ " in length, internally, and $\frac{7}{8}$ " in diameter at and near the section line 4-4; the internal diameter diminishing to $\frac{33}{32}$ " in the region midway between the apertures 22 and 23, with the internal end diameter $\frac{31}{32}$ ". The 20 apertures 20 to 27, inclusive, produce a scale of notes as they are successively uncovered, and the apertures provided by cutting away the parts 29 and 30 produce the two next higher notes in the scale, following that produced by the aperture 27. It will be understood that although the 25 apertures provided by cutting the parts 29 and 30 are located in the body 10 near or opposite the aperture 23, said apertures produce notes higher in the scale than that produced by the aperture 23, due to the differences in the sizes 30 of said apertures and their relative locations. Of course, it will be understood that the positions of the apertures may be varied, and the pitches of the notes can be tuned by a musician to produce a true scale by altering the sizes of the 35 apertures.

The body 10 and mouthpiece 15 are preferably made of molded material which facilitates the production of accurately formed and proportioned members, but wood or other material 40 may be used.

Changes may be made in details of construction

without departing from the scope of my invention.

I claim:

1. A musical instrument of the wood wind type having a tone producing mouth piece and a generally cylindrical body tapered throughout the major portion of its length to a closed outer end, said body providing a closed tone chamber and having a plurality of tone holes communicating with said chamber and arranged to be covered by the fingers of the hands whereby the lowest or fundamental note of the instrument is produced when all said holes are closed, and said mouth piece having a cylindrical portion slidably mounted in said body remote from its closed end to provide an adjustable extension thereof whereby the length of the tone chamber may be varied for changing the pitch of all of the produced notes proportionately throughout the range of the instrument. 20

2. A musical instrument of the wood wind type having a tone producing mouth piece and a generally cylindrical body tapered throughout the major portion of its length to a closed outer end, said body providing a closed tone chamber and having a plurality of tone holes communicating with said chamber and arranged to be covered by the fingers of the hands whereby the lowest or fundamental note of the instrument is produced when all said holes are closed, said body having frangible wall portions surrounded by means designating the location, shape and size thereof, said portions being removable from said body to provide additional tone controlling holes, and said mouth piece having a cylindrical portion slidably mounted in said body remote from its closed end to provide an adjustable extension thereof whereby the length of the tone chamber may be varied for changing the pitch of all of the produced notes proportionately throughout 40 the range of the instrument. 30
